STICK HOLDER

Leo D. Overland, Brooklyn, N. Y.

Application March 5, 1945, Serial No. 581,158

1 Claim. (Cl. 294—87)

1

This invention is concerned with multiple stick holders, the same being devices to hold releasably in preselected position a plurality of sticks which are used as handles for frozen confections.

These sticks are elongated and have rectangular transverse cross-sections so that the longitudinal surfaces of each of them comprise two narrow edges and two wide faces.

Although considerable care is exercised to maintain the cross-sectional dimensions constant, commercially, the width and thickness of the sticks are subject to substantial variations.

Present-day multiple stick holders may, in general, be classified in two categories. One type of multiple stick holder includes a plurality of vertically extending elements, against each of which a stick is pressed simultaneously by a horizontally movable element, the direction of travel of which intersects the vertical element. In the other type of multiple stick holder, a central plate is disposed between an upper and a lower plate, all the plates being provided with registered apertures. The central plate is shiftable relative to the other two plates in such manner that when gripping a stick, an edge of each aperture in the central plate is pressed against a longitudinal surface of the stick while a pair of registered edges of the corresponding apertures in the upper and lower plates are pressed against the opposite longitudinal stick surface. In this latter type of stick holder, it is now the practice to have a portion of the edge of each aperture engage a narrow edge of the stick, regardless of whether or not a wide face of the stick is additionally engaged.

Due to the aforementioned constructions, neither type of present-day commercial multiple stick holder is able to grip a large number of sticks in such manner that all the sticks are held tightly enough to prevent some from being pulled out of the stick holder, particularly when the stick holder is pulling from a mold sticks having confections frozen thereon.

More specifically in the case of the first type of stick holder, a non-uniform holding action occurs when some sticks are thicker than others. The thick sticks prevent the horizontally movable members from engaging firmly the thinner sticks.

In the case of the second type of stick holder, a non-uniform holding action occurs where some sticks are broader than others. The broader sticks prevent the stick holder from gripping tightly the narrower sticks, since after engaging the narrow edges of the broader sticks, the central plate can not shift enough more to suffi-

2

ciently engage the narrow edges of the narrower sticks.

Thus in both types of stick holders, movement of the stick gripping members is limited by their inability to further compress the larger sticks.

It is a principal object of the present invention to provide an improved multiple stick holder which grips with substantially the same firmness a plurality of sticks whose widths and thicknesses vary materially, although they are all of the same order of size.

In general, I carry out this object by providing a stick holder of the second type, i. e., one comprising three superimposed gripping members, of which the middle one is shiftable relative to the top and bottom ones, and forming registered apertures in said three members. The outline and dimensions of said apertures are so selected, proportioned and arranged with regard to the relative movement of the gripping members and the order of size of the sticks that the sticks are engaged only on their wide faces, there being substantially no engagement on the narrow edges. This latter feature is of extreme importance, since if the apertures are designed to engage the narrow edges of sticks of average width and if a few overwide sticks are placed in the stick holder, such sticks will prevent the stick holder from fully closing to properly engage the wide faces. Furthermore, the apertures are designed to bow or bend slightly the wide faces thereby compensating for variations in the thicknesses of the sticks. Preferably, the three gripping members are so relatively moved that the middle member is shifted normal to the wide faces of the sticks, although it will be appreciated that it will suffice, in accordance with the spirit of my invention, to shift the middle member obliquely in such manner that it merely has a component of movement normal to the wide faces of the sticks.

It is another object of my invention to provide a multiple stick holder of the character described in which the three gripping members can be assembled or taken apart with great ease.

An additional object of the invention is to provide a multiple stick holder having a novel safety feature for protecting the fingers of an operator.

A further object of the invention is to provide a multiple stick holder which comprises relatively few and simple parts, and which is rugged in construction, economical to manufacture, and simple and highly efficient in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claim.

In the accompanying drawings, in which is shown one of the various possible embodiments of my invention,

Fig. 1 is a top plan view of a multiple stick holder embodying my invention, the handle being shown in closed or gripping position;

Fig. 2 is a sectional view therethrough taken substantially along the line 2-2 of Fig. 1;

Fig. 2a is an enlarged fragmentary sectional view taken substantially along the line 2a-2a of Fig. 2;

Fig. 3 is an end view of the stick holder;

Figs. 4 and 5 are sectional views taken substantially along the lines 4-4 and 5-5, respectively, of Fig. 1; and

Fig. 6 is a view similar to Fig. 5, but with the handle illustrated in open or releasing position.

Referring now to the drawings, I have there shown a multiple stick holder 10 designed to releasably grip a plurality of elongated flat wooden sticks S of the type customarily employed in the manufacture of handled frozen confections. Said sticks have a cross-section of rectangular outline, best shown in Fig. 1, thereby providing two elongated wide faces F and two elongated narrow edges E. All of the sticks are of the same order of size. For example, said sticks may be about $\frac{1}{4}$ of an inch wide and about $\frac{1}{8}$ of an inch thick. However, it is commercially impractical, as noted earlier, to keep these dimensions within close tolerances.

In general, the stick holder 10 comprises a hollow elongated box-like member 12, including an elongated top plate 14 which forms the upper gripping member and an elongated bottom plate 16 which forms the lower gripping member. These two plates are parallel to and spaced from each other. Intermediate said plates, I provide a third gripping member in the shape of an elongated central plate 18 which is parallel to and spaced from the top and bottom plates. A pair of spaced handles 20, one at each end of the stick holder, expedite manipulation of the stick holder and carrying of the same from place to place. In addition, a manually actuatable locking handle 22 is employed to shift the central gripping member 18 toward and away from closed position.

The box 12 may be conveniently stamped or pressed from a light gauge non-corrodible metal, such as Monel metal, or stainless steel, and is preferably made in two sections so as to permit easy separation of the various elements of the stick holder for cleaning.

The upper box section includes the top plate 14 from whose longitudinal edges depend flanges 24 having inturned free ends 26 upon which the bottom and central plates are supported. The bottom box section includes the bottom plate 16 from whose longitudinal edges flanges 28 project into frictional engagement with the top plate 14. Said bottom section is slidably received on the inturned ends 26, the limit of its insertion into the upper section being determined by abutment of notches (not shown) at an end of said bottom section against stops 30 at an end of the upper box section.

The central plate 18 has dependent, longitudinal and end flanges 32, 33 which rest upon

the bottom plate 16 and thus space said central plate a proper distance from the bottom plate. Said central plate is narrower than the upper and lower box sections, so that it may be shifted from the front to the back thereof.

The manually actuatable locking handle 22 for effecting this shifting movement comprises an elongated metallic strip having terminal extensions 34 one near each manipulating handle 20. Said extensions are pivotally secured by rivets 36 to ears 38 struck from the top plate 14. Further, each extension is interconnected by a link 40 to a flat coupling member 42 which is constrained to move with the central plate 18. Said coupling member is formed from heavy gauge sheet material and includes an upstanding body section 44 resting on the top plate 14. Said member is pivotally attached to an end of the link 40 and has two dependent legs 46, 48 which are received in matching apertures 50, 52 in the central plate 18. Each leg has a large projection 54 located between the central plate 18 and top plate 14 to maintain the proper spacing therebetween. The body section 44 and one of the projections 54 between them define a retaining slot 56 which slidably receives a portion of the top plate 14 to prevent the coupling member 42 from being accidentally disconnected from the central plate. Both legs 46, 48 freely pass through guiding slots 58 in the top plate 14, thereby permitting free sliding movement of the coupling member. These slots are longer than the retaining slot 56 so that when the locking handle is moved beyond its fully open position (shown in Fig. 6), the coupling member can be lifted out of engagement with the central plate at such time as the stick holder is to be disassembled.

With the foregoing construction, movement of the locking handle from the position shown in Fig. 6 to that shown in Fig. 5 will cause the central plate 18 to shift from the back toward the front of the stick holder. As will later be explained, this movement of the center plate effectuates a gripping action on the sticks S.

In the closed or gripping state of the stick holder, shown in Fig. 5, it will be observed that the rivet 60 which pivotally interconnects an end of the link 40 to a terminal extension 34 is disposed below a line running between the rivet 36 and the rivet 62 which pivotally interconnects the other end of the link 40 to the coupling member 42. Thus the handle is locked beyond a dead center position when closed. If desired, a slot 64 may be formed in an end of the link 40 to receive the rivet 62.

Although cooperation between the guiding slots 58 and flat legs 46, 48 affords the desired control of the front-to-back movement of the central plate 18, additional guiding means may be provided to reduce the wear on said slots and legs. Such means comprises three depending studs 66 secured to the top plate 14 and slidably received in front-to-back slots 68 in the central plate 18.

It may also be desired to employ additional means to maintain the proper spacing between the top and central plates, and such means in the instant embodiment of my invention comprises a pair of upstanding pins 70 supported on the central plate 18 and slidably engaging the lower surface of the top plate.

Heretofore, much trouble has been experienced in handling stick holders, particularly after the same have been chilled during freezing of the confections and it is desired to pull the frozen con-

fections and sticks out of a mold. It has been found that if an operator at this time, when wrapping her fingers around the manipulating handles 20, touched the locking handle 22, said locking handle would spring upwardly with considerable force. In commercial operation, this has bruised and broken many an operator's finger. Such action is probably due to front-to-back contraction of the box-like member 12 which compresses the link 40 and extension 34 causing the latter to press against the top plate 14. In effect this cocks the locking handle so that when it receives an impulse sufficient to raise the rivet 60 above dead center, said handle will fly up rapidly.

It has been proposed to overcome this difficulty by placing all parts of the locking handle 22 far enough away from the manipulating handles 20 so that the locking handle 22 could not be touched even accidentally when the stick holder was lifted. However, this further complicated operation of the stick holder since an operator desiring to release the sticks could not reach the locking handle with her fingers while at the same time holding the manipulating handles.

In accordance with a feature of the present invention, I overcome such trouble by providing laterally extending portions, such as reverse bends 12, at opposite ends of the locking handle 22. These reverse bends are disposed close enough to the manipulating handles 20 to allow them to be reached by the finger tips of an operator who is holding said manipulating handles. However, said reverse bends permit the terminal extensions 34 to be spaced far enough away from said manipulating handles so that they cannot be touched even accidentally by an operator holding the stick holder by the manipulating handles. The terminal extensions are made much longer in a front-to-back direction than the corresponding dimension of the reverse bends 12, so as to provide ample room on the manipulating handles within which an operator can grasp the same without endangering her fingers.

The several plates 14, 16 and 18 each have a set of apertures 74, 76 and 78, the apertures in each plate being mutually arranged in a manner which is determined by the type of multiple frozen confection mold with which the stick holder 10 is adapted to be employed. Ordinarily, a multiple frozen confection mold has the several cavities thereof disposed in a plurality of parallel rows with the cavities in each row registered along lines running perpendicular to said rows. The sets of apertures 74, 76, 78 are arranged in such manner. Said apertures further are so mutually arranged and of such size and shape that when the locking handle 22 is in the open position shown in Fig. 6 the overlying edges of a group of apertures are in substantial alignment and define an effective aperture much larger all around than the cross-sectional contour of a stick whereby a stick may be placed in the same easily. Such effective aperture will be referred to hereinafter as the "receiving aperture."

Said groups of apertures furthermore are of such configuration that when the locking handle 22 is in the closed position shown in Fig. 5, having moved the central plate as far forward as possible, the effective aperture G (Fig. 2a) defined by an overlying group of apertures 74, 76, 78 is smaller all around than the receiving aperture. This latter effective aperture will be referred to hereinafter as the "gripping aperture." Said gripping aperture is elongated and its longitudinal axis is transverse to the direction of move-

ment of the central plate. The longitudinal edges of the gripping aperture are substantially straight so that they can flatly press against the wide faces of a stick.

Pursuant to my invention, these edges are parallel to each other, have a length at least equal to the width of an average stick and are spaced apart a distance slightly less than the thickness of the thinnest stick likely to be used in the stick holder. By virtue of this construction, the stick holder is able to pick up a plurality of sticks having cross-sectional dimensions of the same order but varying widely from one another.

My improved stick holder is able to function in this manner because when the central plate is shifted to fully closed or gripping position, there is no tendency for the apertures in the plates to engage the narrow edges of average width sticks whereby to prevent the central plate from moving to fully closed position when an overwide stick is in the stick holder. If some overwide sticks are in the stick holder, their narrow edges will merely be lightly engaged, since the opposed straight portions of longitudinal edges of the gripping aperture are at least as long as the width of an average stick. This is in contrast with present-day commercial multiple stick holders in which the gripping apertures are designed to engage the narrow edges of the narrowest sticks. If overwide sticks are present in such former stick holder, by the time said overwide sticks have been engaged by the apertures, substantial resistance is offered to further movement and it requires a strength greater than that possessed by an ordinary operator to thereafter move the central plate to a position in which it firmly engages the narrow edges of the average sticks, much less those of an underwidth stick.

It will thus be appreciated that with the stick holder herein described, the center plate can always be moved to the fully closed position for which it was designed. As mentioned earlier, the width of the gripping aperture is less than the thickness of the narrowest stick placed in the stick holder. Since the several plates are mutually spaced apart, the use of a gripping aperture of such size will cause the sticks to be slightly bowed or bent when gripped in the stick holder, as shown exaggeratedly in Figs. 3-5. This bowing action causes substantial frictional engagement between the longitudinal edges of the gripping aperture and opposite wide faces of a stick. As even the thinnest stick will be bowed, it will be obvious that thicker sticks will likewise be bowed, so that the stick holder will firmly grip sticks of all thicknesses. Furthermore, it will now be appreciated that by enabling the central plate to move to fully closed position, I make certain that even the thinnest sticks will be gripped.

It will be understood from the foregoing description of the operation of the stick holder that the actual shapes of the apertures 74, 76, 78 are not important, it being merely necessary for each of these apertures to have one straight edge which is adapted to press against a wide face of the stick, this straight edge in closed position of the central plate being at least as long as the width of an average stick and forming one of the opposed straight portions of a longitudinal edge of a gripping aperture. It will further be appreciated that each aperture should include an angular, but not necessarily straight, portion running from at least one end of such straight edge, so as to properly orient the stick

before gripping the same and elongate the effective aperture when the locking handle is opened. In the illustrated embodiment of my invention, I have shown all the apertures as having a hexagonal shape. However, it will be understood from the preceding that other shapes, such as rhombic, triangular, and semi-circular, can serve equally well.

I prefer not to wholly rely upon the frictional engagement between the longitudinal straight edges of the effective apertures and the wide faces of the sticks to secure the sticks in the stick holder, and to supplement this locking action, I provide on each said longitudinal edge, one or more piercing projections, tines, or sawteeth 80. Such projections make certain that sticks of all thicknesses will be firmly gripped. More specifically, when sticks of various thicknesses are in the stick holder, the projections will be imbedded in both thick and thin sticks even if the presence of a particularly thick stick prevents the longitudinal straight edges of a gripping aperture from engaging the flat faces of the thinner sticks.

It should be noted, therefore, that the term "straight" as used herein to describe a longitudinal edge portion of a plate aperture or gripping aperture, denotes straight apart from the projections, i. e., an edge portion which in closed position will engage a wide face from edge to edge thereof.

Since one longitudinal straight portion of the gripping aperture comprises a longitudinal edge of an aperture 78 in the central plate, and the other longitudinal straight portion of the gripping aperture comprises a longitudinal edge in each associated aperture of the upper and lower plates, each of said apertures need only be provided with one projection along the longitudinal edge thereof which serves as part of the effective aperture. As shown in Fig. 5, said projections imbed themselves in the wide faces of the sticks gripped by the stick holder, thus effectively preventing any vertical shifting thereof.

If desired, a set of apertures 82 may be formed, one in each of the top, central and bottom plates, said apertures being large enough to easily pass a finger and being arranged to be registered when the plates are in closed position. This set of registered apertures can be used to visually ascertain the condition of the frozen con-

fection or to allow the surface thereof to be touched.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

A stick holder comprising a pair of plane gripping members, means to mutually detachably attach said members in spaced parallel relationship, a third plane gripping member slidable between said pair of gripping members in a direction parallel to the planes thereof, a handle, a coupling member disposed above said top gripping member and having a portion extending through a slot in said top member and detachably engaged with said third member, co-adjusting means on the coupling member and top gripping member only to captively mount said coupling member for slidable movement on said top gripping member, means to mount said handle on said top gripping member for movement relative thereto, and means to interconnect said handle and said coupling member so that movement of said handle will move said third gripping member relative to said pair of gripping members to grip a stick.
